K. DOUGAN,
APPAREL BELT BUCKLE,
APPLICATION FILED APR. 28, 1921.

1,398,633.

Patented Nov. 29, 1921.

UNITED STATES PATENT OFFICE.

KENNEDY DOUGAN, OF MINNEAPOLIS, MINNESOTA.

APPAREL-BELT BUCKLE.

1,398,633.

Specification of Letters Patent. Patented Nov. 29, 1921.

Application filed April 28, 1921. Serial No. 465,263.

To all whom it may concern:

Be it known that I, KENNEDY DOUGAN, a citizen of the United States, residing at Minneapolis, in the county of Hennepin and State of Minnesota, have invented certain new and useful Improvements in Apparel-Belt Buckles, of which the following is a specification.

My invention relates to improvements in apparel belt buckles of the species in which the free end of the belt is hidden beneath the fixed end, and the objects of my improvements are to provide a belt that will not abrade the apparel of the wearer, be durable and slightly and conceal the adjustable end of the belt when being worn, and is a further development of the invention disclosed in my application #461,261, filed 4-14-21.

I attain these objects by the means illustrated in the accompanying drawings, in which,—

Figure 1 is a view of the body side of the belt buckle with the fixed end of the belt and the adjustable end shown in place and partly broken away.

Fig. 2 is a longitudinal section of Fig. 1 showing the means for holding both ends of the belt.

Fig. 3 is a similar view with the belts and holding means omitted.

Fig. 4 is a top view of the buckle.

Fig. 5 is an end view of the buckle looking toward the right with belts and holding means omitted.

Fig. 6 is a central transverse section of Figs. 1 to 4 inclusive, with all movable parts omitted.

Fig. 7 is a transverse section on the line A—Fig. 2.

Fig. 8 is a perspective of a portion of Fig. 3 looking toward the right. Fig. 9 is an end view of the buckle with all movable parts omitted and shows how that part of the buckle which comes in contact with the clothing may be formed to obviate undue wear.

Figs. 10, 11 and 12 show a modified form of the invention on a reduced scale to be described later.

Referring to the drawings:

1 is the fixed end of the belt; 2 the adjustable end of the belt which is held between flat surface 3 of the buckle and the belt holding device 4 operating in slanting grooves 5. 6 is the device for holding the

fixed end of the belt and is provided with teeth 7 as clearly shown in Fig. 7.

Projecting from the face plate 3 are the parallel sides 8; these sides 8 are formed as shown in all the figures especially 5 to 8 inclusive and form tapering grooves 5 between portion 9 and plate 3. When securing the fixed end of the belt, belt holding device 6 is slipped toward the center of the buckle and the end of the belt placed under teeth 7; part 6 is then pushed to the left with one hand while pulling on the belt with the other and the teeth crowded through the belt until the part 6 becomes jammed between plate 3 and part 9. Attention is called to the fact that the inner edges of parts 9 are curved in the manner shown so as to form a gradually decreasing angle with which part 6 contacts when being moved into place.

Except that part 4 is not provided with teeth what is said of part 6 is also applicable to part 4 which is provided with outwardly turned portion 4' and the inwardly turned portion 4''. When inserting the adjustable end of the belt, part 4 is drawn toward the center of the buckle and the finger pressed against end 4'' which raises the end 4' allowing the belt to pass under it, after which pressure is removed from end 4'' and the belt pushed through.

In tightening the adjustable end of the belt, part 4 is pushed to the right at the same time that belt 2 is pulled to the right. In placing parts 6 and 4 in the buckle the parallel sides 8—9 are sprung out slightly at the center to admit of these parts being put in place; said parts are prevented from coming out of the buckle by the inwardly extending projections 10; these projections are formed on the lower inner side of the buckle only.

Referring to Figs. 10, 11 and 12:

Fig. 10 shows the buckle in longitudinal section.

Fig. 11 is an end view of the buckle with all parts removed.

Fig. 12 shows a device in all respects similar to belt holding device 4 shown in Figs. 1 and 2, except that it is provided with the outstanding lugs 4^a which are adapted to move back and forth in the grooves 5. It will be noted that in the form of the invention heretofore described, that the plate 3 forms one side of the groove, while in the form shown in Figs. 10 and 11 110

the groove is spaced away from the bottom of the plate and formed in the sides 8.

The operation is obvious.

I claim:

- 5 1. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 50
- 10 2. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 55
- 15 3. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 60
- 20 4. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 65
- 25 5. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 70
- 30 6. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 75
- 35 7. A belt buckle comprising a plate having inwardly extending parallel sides provided with shoulders parallel with said plate transversely, spaced away therefrom and tapering from the longitudinal center of said buckle toward each end with a decreasing taper, and a device adapted to hold the end of a belt between said shoulders and said plate. 80
- 40 8. A belt buckle comprising a plate having inwardly extending parallel sides provided with shoulders parallel with said plate transversely, spaced away therefrom and tapering from the longitudinal center of said buckle toward each end with a decreasing taper, and a device adapted to hold the end of a belt between said shoulders and said plate, and means for retaining the movable parts inside of the buckle. 85
- 45 9. A belt buckle including a front plate having parallel sides projecting from the

back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 90

10. A belt buckle including a front plate having parallel sides projecting from the back thereof, grooves formed between an inwardly turned portion of said sides and said front plate, said grooves tapering from the longitudinal center of the buckle toward either end with a decreasing taper, and means for holding both the fixed and adjustable ends of the belt to the buckle. 95

11. A belt buckle comprising a plate having inwardly extending parallel sides provided with shoulders parallel with said plate transversely, spaced away therefrom and tapering from the longitudinal center of said buckle toward each end with a decreasing taper, and a device adapted to hold the end of a belt between said shoulders and said plate. 100

12. A belt buckle comprising a plate having inwardly extending parallel sides provided with shoulders parallel with said plate transversely, spaced away therefrom and tapering from the longitudinal center of said buckle toward each end with a decreasing taper, and a device adapted to hold the end of a belt between said shoulders and said plate, and means for retaining the movable parts inside of the buckle. 105
